UNITED STATES PATENT OFFICE

128,970

DESIGN FOR A LACE

Joseph A. Sutton, New York, N. Y.

Application July 11, 1941, Serial No. 102,024

Term of patent 3½ years

To all whom it may concern:

Be it known that I, Joseph A. Sutton, a citizen of the United States of America, residing in New York city, county of New York, and State of New York, have invented a new, original, and ornamental Design for a Lace, of which the following is a specification, reference being had to the accompanying drawing, forming part thereof, wherein the figure is a plan view of a piece of

lace showing my new design, the same being depicted on a dark background for the purpose of bringing out more clearly the details of the design.

I claim:

The ornamental design for a lace, substantially as shown and described.

JOSEPH A. SUTTON.
